UNITED STATES PATENT OFFICE

FREDERICK J. PIERCE, OF SARANAC LAKE, NEW YORK

FOOT IMPRESSION MOLD

Application filed January 25, 1929. Serial No. 334,953.

This invention relates to an improved device embodying complementary means for taking foot impressions in a plaster of Paris cast to aid in the construction of footwear.

More specifically, the invention has reference to an improved and simple method and means for obtaining a plaster of Paris impression of the foot for the purpose of making custom made shoes to measure, arch supports, foot braces, elastic stockings or other mechanical device or support which may be prescribed by a doctor, surgeon or chiropodist.

Briefly stated, the device comprises a mold of foot shaped design embodying a base, and a sectional foot shaped shell for confining the plaster of Paris about the foot to produce accurate impressions.

In the drawings:

Figure 1 is a side elevational view of the improved mold, showing the manner in which the cast is made and indicating the foot positioned therein in dotted lines.

Figure 2 is a view of the mold with the sections of the shell swung open.

Figure 3 is a vertical sectional view through the mold.

In the drawings, the reference character 6 designates a main base which is of appropriate dimensions and somewhat ovate in outline. This is provided on its bottom with rubber tipped rests or supporting feet 7. Rising from the back of the plate is a pimple 8 on which the sections of the shell like mold 9 are hingedly mounted. As shown in Figure 2, the shell is made up of a pair of duplicate half sections and each section is composed of a lower portion 10 and an upper portion 11. The upper portion in each instance has an opening 12 formed therein and on the outside and in register with the opening is the small receptacle 13 operated as a funnel. As before indicated this mold is of general foot shaped form. In carrying out the molding process, I provide a toe shield 14 so constructed as to permit it to be fitted over the toes to prevent accumulation of the plaster of Paris between the toes. In addition, I provide a pair of wires or tapes 15 and 16 located in the front and back portions of the mold respectively as

shown in Figure 1 and centrally arranged in order to serve in slicing the plaster of Paris cast into half sections to permit removal.

The reference character 17 in Figure 3, designates a pad which is placed upon the top 55 of the main base 6. This pad is preferably constructed of two similar sections of cardboard 18.

A suitable retaining clip 25 may be attached to the main base, to hold the sections 60 of the mold closed. Any appropriate fastening means may be employed for this purposes such as hook and eyes or mere pivoted clips.

The method of use is as follows: 65

The foot should be clean and dry with the hair shaved off up to about three inches above the ankle joint. The removable toe shield or protector is then slipped over the fore foot in order to cover the toes as indicated in dotted lines in Figure 1. Then apply petroleum jelly or dust the foot thoroughly with talcum powder, rubbing it well into the pores. I then place the oval shaped cardboard pad on the main platform of the foot 75 impress and place the foot as nearly in the middle as possible.

The wires or tapes 15 are then placed in position. It is the object here to place the wire 15 up and over the forward portion and 80 ankle somewhat as indicated in Figure 1 and to place the wire 16 against the heel and extended up and out through the top of the mold. The extended end portion may be attached to prevent temporary displacement 85 by wrapping a piece of adhesive tape around the ankle and wire end.

The patient may sit on a chair but preferably assumes a standing posture with the body weight equally distributed on both feet. 90

The sections of the mold are then closed, it being necessary to first close the lower portions 10 of the half sections and to temporarily leave the upper portions 11 of said half sections open. I dissolve gradually the 95 contents of one box of plaster of Paris in an appropriate amount of lukewarm water, stirring constantly until a free flowing plaster of Paris is obtained, and I then pour it into the closed lower, section or division of 100

the mold. Then the upper portions 11 are closed and fastened in place and the remaining plaster is poured into them through the funnels 13 and the openings 12, the mold 5 being filled to substantially the top. The foot is allowed to remain here for a predetermined length of time. Then the mold is opened and wires 15 and 16 are pulled down to slice the cast into two parts. Then I 10 move the two sections or parts of the cast from the foot. The cardboard section of the pad 17 adheres to the plaster of Paris cast.

It is believed that by considering the description in connection with the drawings, a clear understanding of the operation, construction, and features and advantages of the invention will be clear. Consequently a 15 more lengthy description will be regarded 20 as unnecessary.

Minor changes in the shape, size and rearrangement of parts coming within the field of invention claimed may be resorted to, if desired.

25 I claim.

In a structure of the class described, substantially ovate base plate having supporting feet, a hinge pintle connected to and rising from one end of said plate, a foot 30 shaped molding shell comprising a pair of duplicate half sections hingedly mounted on said pintle, each half section being composed of upper and lower relatively swingable portions, said upper portions being formed with 35 filler openings, and adjacent receptacles mounted on and projecting laterally from the sides of the upper portions and communicating with the openings and operating as funnels.

40 In testimony whereof I affix my signature.
FREDERICK J. PIERCE.
